(57) **CLAIM**

The ornamental design for an absorbent sacral wound dressing, as shown and described.

DESCRIPTION

FIG. 1 is an isometric view of an absorbent sacral wound dressing;

FIG. 2 is a top side view thereof;

FIG. 3 is a bottom side view thereof;

FIG. 4 is a front side view thereof, where a back side view is not illustrated as it is a mirror image of the front side view; and,

FIG. 5 is a right side view thereof, where a left side view is not illustrated as it is a mirror image of the right side view. In FIGS. 1 and 3-5 the broken lines show portions of an absorbent sacral wound dressing that form no part of the claimed design.
